DISTRIBUTOR VACUUM CONTROL

John P. Coffin, Anderson, Ind., assignor to General Motors Corporation, Detroit, Mich., a corporation of Delaware

Filed Oct. 14, 1960, Ser. No. 62,579
12 Claims. (Cl. 200—31)

This invention relates to distributors for internal combustion engines and more particularly to vacuum control apparatus for such distributors.

One of the objects of this invention is to provide a vacuum control arrangement for a distributor wherein means are provided for adjusting the compression of the spring of the vacuum unit and thus the point of cut-in of the unit.

Another object of this invention is to provide a vacuum control assembly for a distributor wherein the casing of the vacuum unit that contains the diaphragm is shiftable relative to a fixed supporting bracket and wherein this bracket includes means for limiting movement of the diaphragm to thereby vary the compression of the vacuum unit spring when the casing is shifted relative to the bracket.

Further objects and advantages of the present invention will be apparent from the following description, reference being had to the accompanying drawings wherein preferred embodiments of the present invention are clearly shown.

In the drawings:

FIGURE 1 is a side view partly in section illustrating a distributor that is fitted with the vacuum control assembly of this invention.

FIGURE 2 is a sectional view taken along line 2—2 of FIGURE 1.

FIGURE 3 is a sectional view of a part of the vacuum control assembly of this invention and illustrating a change in position of the vacuum unit relative to the supporting bracket and a change in compression of the vacuum unit spring.

FIGURE 4 is a modified vacuum control assembly made in accordance with this invention.

Referring now to the drawings, and more particularly to FIGURE 1, the reference 10 generally designates a distributor which has a base 12 and a breaker plate 14. The base 12 supports a shaft 16 which is driven by the engine and this shaft carries the usual cam 18. The breaker plate 14, as is well known to those skilled in the art, is shiftable relative to the base 12 and the cam 18 and carries a set of breaker contacts (not shown) which are opened and closed by a rotation of the cam 18.

The vacuum control assembly of this invention is generally designated by reference numeral 20. This vacuum control assembly includes a vacuum unit 22 that is comprised of the sheet metal casings 24 and 26. The sheet metal casing 24 is provided with a conduit portion 28 that is connected with a source of vacuum. A diaphragm 30 is contained within the casings 24 and 26 and is formed of a suitable flexible material such as rubber. It can be seen that the outer annular margin of the diaphragm is positioned between outer annular portions of the casings 24 and 26 with a part of the casing 26 being crimped over at 32 in order to provide a tight fit between the outer margin of the diaphragm 30 and the casings 24 and 26.

The diaphragm 30 is connected with an actuating rod 34 by means of washers 36 and 38. It can be seen that the rod 34 is headed over at 40 in order to provide a tight fit between the washers 38 and 36 and the part of the diaphragm fitting between these washers. The particular method of securing the actuating rod to the diaphragm 30 forms no part of this invention and may be

2

made in any conventional fashion. It is seen that a spring 42 is interposed between the washer 36 and one end of the casing 24 in order to urge the diaphragm 30 in one direction.

5 The casing member 26 carries an externally threaded coupling member 44. This coupling member 44 is formed of a metal material and is spot welded or otherwise secured to the casing member 26. The coupling member 44 has a pair of axially extending slots 46 and 48 which are illustrated in FIGURE 2.

The vacuum unit 22 is supported from the base of the distributor by means of a bracket which is generally designated by reference numeral 50. The bracket 50 has a section 52 which is secured to the base 12 by suitable fasteners 54. The bracket 50 has a bent-down section 56 which is formed with an opening 58 to permit the actuating rod to move through the portion 56 of the bracket 50. In addition to these sections, the bracket 50 is formed with sections of portions 60 and 62 that straddle the coupling member 44 and which have parts that fit within the slots 46 and 48. The sections 60 and 62 of the bracket member 50 thus serve to slidably support the coupling member 44. A pair of nuts 64 and 66 are positioned on opposite sides of the sections 60 and 62 and are threaded onto the coupling member 44 as is clearly apparent from the drawings.

It can be seen that when it is desired to adjust the compression of the spring 42, the nuts 64, 66 are rotated to cause the coupling member 44 to shift relative to the fixed bracket member 50. In FIGURE 3, the coupling member 44 has been shown shifted relative to the fixed bracket member 50 and it is seen that the spring 42 has been compressed. It, of course, will be appreciated that when the coupling member 44 is shifted relative to the bracket, the casings 22 and 26 are likewise shifted with the coupling member since they are connected thereto. The diaphragm 30, however, is prevented from being shifted with the casing members 22 and 26 since it engages the portion 56 of the bracket member which at all times remains fixed. It thus can be seen that the cut-in pressure of the vacuum unit may be simply adjusted by adjusting the nuts 64 and 66 to cause the coupling member 44 and the attached casings 22 and 26 to shift relative to the bracket member 50. It will, of course, be appreciated by those skilled in the art that the rod 34 operates the breaker plate 14, the rod being connected thereto by an up-turned portion of the rod 68 which passes through a suitable opening formed in the breaker plate 14.

50 In the FIGURE 1 embodiment, the bracket member 50 is secured to the underside of the base member 12. It will be appreciated, however, that the bracket member might be secured to the top side of the base member 12 and a suitable slot provided in the base member which would receive the actuating rod 34. It will also be appreciated that the bracket member could be fixed within a suitable slot formed in the base member 12 and the particular connection of the bracket member to the base member forms no part of this invention.

60 Referring now more particularly to FIGURE 4, a modified vacuum control assembly that has an adjustable feature is illustrated. In FIGURE 4 the reference numeral 14 once more designates a breaker plate of the distributor and the reference numeral 34 again designates the actuating rod having the up-turned portion 68 which is positioned within an opening formed in the breaker plate 14. The vacuum unit in FIGURE 4 is designated by reference numeral 22 since it is identical in many respects with the vacuum unit 22 of FIGURES 1 and 3. 65 In the FIGURE 4 embodiment, a coupling member 70 is provided which has external threads and which forms a part of the conduit for applying vacuum to the interior

of the vacuum unit 22. The bracket member in FIGURE 4 is designated in its entirety by reference numeral 72 and it can be seen that it is secured to the base 12 of the distributor by suitable fasteners 74. The bracket member 72 has an opening 76 through which the actuating rod passes and has a section 78 which contacts the washer or plate member 80 to limit movement of the diaphragm 30 in one direction. The bracket member has another section 82 which is formed with an opening that receives the coupling member 70. A pair of nuts 84 and 86 are positioned on opposite sides of the section 82 of the bracket member 72 and it can be seen that by rotating the nuts 84 and 86 the entire vacuum unit may be adjusted relative to the bracket. It also can be seen that the washer member 80 passes through a suitable opening formed in the casing member 26 so that upon adjustment of the vacuum unit the diaphragm is prevented from shifting due to the contact between the washer 80 and the section 78 of the bracket. It will be apparent from the foregoing that the compression of spring 42 may be adjusted by rotating the nuts 84 and 86 in the required fashion to cause the vacuum unit to shift relative to the bracket member 72.

While the embodiments of the present invention as herein disclosed constitute preferred forms, it is to be understood that other forms might be adopted.

What is claimed is as follows:

1. In combination, a distributor having a base, a breaker plate shiftable relative to said base, a vacuum control assembly for shifting said breaker plate including an actuating rod, said vacuum control assembly including casing means, a diaphragm shiftable relative to said casing means, a spring interposed between said diaphragm and casing means for urging said diaphragm in one direction, means connecting said diaphragm with said actuating rod, a bracket member secured to said base, means forming a shiftable connection between the casing means of said vacuum unit and said bracket, and stop means integral with said bracket for preventing movement of said diaphragm and actuating rod in one direction when said casing means is shifted in one direction to vary the compression of said spring and when no vacuum is applied to said unit.

2. In combination, a distributor having a base, a breaker plate shiftable relative to said base, a vacuum control unit including casing means and a diaphragm, means interconnecting said diaphragm and said breaker plate, support means connected between said distributor base and said vacuum unit casing means for providing relative movement between said casing means and said distributor base, means fixed with respect to said base preventing movement of said diaphragm relative to said base in one direction when no vacuum is applied to said unit whereby said breaker plate is not shifted when said casing means is moved relative to said base, and a spring interposed between said casing means and diaphragm for urging said diaphragm into engagement with said limiting means.

3. In combination, a distributor having a base, a breaker plate shiftable relative to said base, a vacuum unit including casing means and a diaphragm, support means connected with said distributor base and said casing means and providing for relative movement between said casing means and said distributor base, a spring interposed between said casing means and said diaphragm for urging said diaphragm in one direction, stop means fixed with respect to said base positively preventing movement of said diaphragm in one direction under the influence of said spring, and means connecting said diaphragm and said breaker plate.

4. In combination, a distributor having a base, a breaker plate shiftable relative to said base, a vacuum unit including casing means and a diaphragm, a spring interposed between said casing means and diaphragm for urging said diaphragm in one direction, means interconnecting said diaphragm and said breaker plate, stop means

fixed with respect to said base preventing movement of said diaphragm under the influence of said spring relative to said distributor base in one direction of movement of said diaphragm when no vacuum is applied to said unit, and means providing a shiftable connection between said casing means and said distributor base whereby said casing means may be shifted relative to said distributor base to vary the compression of said spring without shifting said breaker plate.

5. A vacuum control assembly for actuating the breaker plate of a distributor or the like comprising, bracket means, a vacuum unit including casing means and a diaphragm, means slidably supporting said casing means fixed with respect to said bracket means on said bracket means, means for preventing movement of said diaphragm in one direction relative to said bracket means when said casing means is shifted relative to said bracket means in one direction, and resilient means interposed between said casing means and said diaphragm, the compression of said resilient means being varied when said casing means is shifted relative to said bracket means.

6. A vacuum control assembly for actuating the breaker plate of a distributor or the like comprising, a vacuum unit including casing means and a diaphragm, an externally threaded coupling member secured to said casing means, a spring interposed between said casing means and said diaphragm, means engaging the threaded portion of said coupling member for shifting said casing means relative to a bracket means, and means fixed with respect to said bracket means for preventing movement of said diaphragm in one direction relative to said bracket means when said casing means is shifted in one direction relative to said bracket means, whereby shiftable movement of said casing means relative to said bracket means varies the compression of said spring.

7. A vacuum control assembly for actuating the breaker plate of a distributor or the like comprising, a vacuum unit having casing means and a diaphragm, an externally threaded coupling member secured to said casing means, bracket means, a pair of slots formed in said coupling member, means on said bracket means positioned within said slots whereby said coupling member may slide relative to said bracket means but is prevented from rotating with respect thereto, nut means threaded onto said coupling member and engaging a portion of said bracket means for causing said coupling member to be shifted relative to said bracket means when said nut means is rotated, a spring interposed between said diaphragm and said casing means the compression of which is varied when said coupling member is shifted relative to said bracket means, and an actuating means connected with said diaphragm.

8. A vacuum control assembly for actuating the breaker plate of a distributor or the like comprising, a vacuum unit including first and second casing members and a diaphragm secured thereto, an externally threaded coupling member secured to one of said casing members, a bracket member, means forming a shiftable connection between said bracket member and said externally threaded coupling member, nut means threaded on said externally threaded coupling member and engaging at least a portion of said bracket member to provide for shiftable movement of said coupling member relative to said bracket member, a spring interposed between one of said casing members and said diaphragm, means integral with said bracket member for limiting movement of said diaphragm in one direction under influence of said spring, and an actuating rod connected with said diaphragm and passing through a portion of the bracket member which limits movement of said diaphragm.

9. A vacuum control assembly for actuating the breaker plate of a distributor or the like comprising, a vacuum unit including first and second casing members, a diaphragm secured to said casing members, a spring interposed between one of said casing members and said diaphragm, an externally threaded coupling member se-

cured to the other of said casing members, an opening in one of said casing members, a bracket member having a portion in alignment with said opening for limiting movement of said diaphragm in one direction under influence of said spring, said bracket member having another section forming a slidable connection with said externally threaded coupling member, nut means threaded on said coupling member for causing said coupling member to be shifted relative to said bracket member, and an actuating rod connected with said diaphragm and passing through the opening in one of said casing members and through the portion of said bracket member that limits movement of said diaphragm in one direction.

10. A vacuum control assembly for actuating the breaker plate of a distributor or the like comprising, a vacuum unit including casing means and a diaphragm connected thereto, a spring interposed between said casing means and said diaphragm for urging said diaphragm in one direction, a coupling member connected with said casing means having an externally threaded portion and having a passage for connecting the interior of said casing means with a source of vacuum, a bracket member, said bracket member having a portion at least partially encircling the threaded portion of said coupling member, nut means threaded on the threaded portion of said coupling member for causing said casing means to be shifted relative to said bracket means, means on said bracket means for limiting movement of said diaphragm in one direction under the influence of said spring, and an actuating rod connected with said diaphragm.

11. A vacuum control assembly for adjusting the breaker plate of a distributor or the like comprising, support means, a vacuum unit including casing means and a diaphragm, a spring interposed between said casing means

and diaphragm for urging said diaphragm in one direction, stop means fixed with respect to said support means for constantly maintaining said diaphragm at a predetermined distance from a given point on said support means when no vacuum is applied to said unit, actuating means connected with said diaphragm, and means forming an adjustable connection between said casing means and said support means whereby the compression of said spring is varied when said casing means is shifted relative to said support means without shifting said diaphragm or actuating means.

12. A vacuum control assembly for adjusting the breaker plate of a distributor or the like comprising, a support means, a vacuum unit including casing means and a diaphragm, a spring interposed between said casing means and diaphragm for urging said diaphragm in one direction, means forming an adjustable connection between said casing means and said support means whereby said casing means may shift relative to said support means, and stop means for maintaining said diaphragm in a position fixed with respect to said support means when said casing means is moved in either direction within a predetermined range of movement, the compression of said spring being constantly varied when said casing means is moved in either direction in said range of movement.
